ADJUSTING DEVICE

Guy O. Conner, Wheeling, W. Va., assignor to
Wheeling Steel Corporation, Wheeling, W. Va.,
a corporation of Delaware

Application July 7, 1934, Serial No. 734,221

12 Claims. (Cl. 113—1)

This invention relates broadly to adjusting devices. It relates more particularly to devices for adjusting or applying retaining devices of the expansible and contractible hollow or discontinuous annular type such as are used, for example, in retaining covers or heads in place on containers or the like and to the application thereof.

Expansible and contractible hollow retaining means are now widely used for various purposes, among the principal of which are retaining heads in place on various kinds of containers, such as sheet metal drums having outward peripheral projections at their mouths, and holding together steel barrels and similar constructions. Most such retaining devices are provided integrally with their own operating means, such as link and lever mechanism, which may be used for expanding and contracting the retaining devices. Retaining devices of this type are, however, relatively expensive, and, although they are eminently suitable for certain purposes, as for use with metal drums which are to be returned and reused, their cost represents too great a proportion of the cost of a filled package to make their use desirable or economical in certain other cases, as when the packages are not intended for reuse but are intended to be discarded or destroyed.

I have provided a very inexpensive but nevertheless highly useful retaining device which may be discarded or destroyed after being used once. In order to reduce to a minimum the cost of the retaining device I do not attach to it any link and lever or other operating mechanism, and in its simplest form it comprises simply an expansible and contractible hollow retaining means having cooperating end portions adapted to be engaged by a separate applying device to move the same to applied position and means whereby the retaining means may be maintained in applied position.

As the retaining device would be extremely difficult to apply by hand tightly enough to most effectively serve its purpose, I provide an adjusting or applying device separate from the retaining device and adapted for use in application of the retaining device, after which other means are employed to maintain the retaining device in applied position and the applying device is removed. The applying device is such that it may be set in place on top of a drum or other container to which a retaining device is being applied and has portions shaped to operatively engage the retaining means adjacent

the ends thereof and means for operating the same to move the retaining means to applied position. The word "apply" and its derivatives are herein used in the same sense as the word "adjust" and its derivatives.

Other details, objects and advantages of the invention will become apparent as the following description of a present preferred embodiment thereof proceeds.

In the accompanying drawings I have shown 10 a present preferred embodiment of the invention, in which

Figure 1 is a plan view of a metal drum having a head in place thereon and showing the application of a retaining device and an applying device for performing such function;

Figure 2 is an elevational view of the upper portion of the drum and other mechanism shown in Figure 1;

Figure 3 is an enlarged partial elevational view, 20 partly in central vertical cross section, similar to Figure 2 and showing the retaining device moved to applied position;

Figure 4 is a partial central vertical cross-sectional view through the construction shown 25 in Figure 3;

Figure 5 is a detail top plan view of one end of the retaining device; and

Figure 6 is a bottom plan view of the applying device with the parts indicated in full lines 30 in one position and in dotted lines in another position.

For purposes of illustration only I have shown the invention as embodied in a retaining device comprising expansible and contractible hollow retaining means adapted to be contracted about a container, such as a metal drum, to maintain a cover or head in place thereon and to be expanded or permitted to expand so as to allow removal of the retaining means so that 40 the cover or head may be removed.

Referring now more particularly to the drawings, reference numeral 2 designates generally a sheet metal drum provided with the usual rolling rings, one of which is shown at 3, and the usual 45 rim bead 4. Applied to the drum is a cover or head 5 which is of the hollow type having an upwardly and outwardly turned flange 6. The flange 6 of the head is adapted to overlie the rim bead 4 of the drum and interposed therebetween 50 is a gasket 7. All of the parts above described may be of standard construction.

For maintaining the head in place on the drum there is provided a retaining device 8 which comprises a hollow expansible and contractible sheet 55

metal retaining member 9 of generally V-shaped cross section, as shown in Figure 3. Riveted to each end of the retaining member 9 by rivets 10 is a member 11, which may also be of sheet metal. The inner end of each of the members 11 is struck up to form a projection 12, for a purpose presently to be described, and the metal at the outer end is reversely turned, as shown at 13, to form a portion of double thickness. Such portion extends downwardly forming an eye 14, for a purpose presently to be described, and also an underlying lug 15 having an opening 16 therein.

In applying the retaining device the same is first loosely put into position about the rim bead 4 and flange 6 in usual manner, as shown in Figure 2. As considerable force is required to tightly contract the retaining device so as to maintain a mechanically-tight and fluid-tight seal between the drum and the head, I provide an applying device, designated generally by reference numeral 17, and which has a base plate 18 adapted to overlie the inner portion of the hollow head 5. On the bottom of the base plate 18 are three downwardly projecting feet or lugs 19, 20 and 21, respectively. These lugs are, respectively, of such height as to cooperate with the top of the head and maintain the base plate in position substantially perpendicular to the axis of the drum. The lugs 19 and 20 are also adapted to lie against the inner surface of the upwardly and outwardly turned flange 6 of the cover and to bear against such flange so as to offer a reaction to the force required to move the retaining device to applied position.

There is also provided as a part of the applying device 17 an upper plate 22. Pins 23 extend upwardly from the base plate 18 and through the upper plate 22. The upper plate is spaced from the base plate, enlarged hub portions 24 of oppositely disposed operating members or arms 25 lying between the base plate and the upper plate. Cotter pins 26 maintain the assembly. The arms 25 are pivotally movable about the pins 23, as indicated in Figure 6. Each arm 25 has a downwardly projecting outer extremity 27 shaped to engage the retaining device 8 and to lie against the respective projections 12 thereof in pressure applying relationship, as shown in Figure 3.

For operating the members 25 there is provided a disc 28 underlying the upper plate 22 and rigidly connected to the base of an operating shaft 29 provided with an operating handle 30. The shaft 29 passes upwardly through the upper plate 22. Underlying the disc 28 and pivoted thereto at opposite sides thereof by pins 31 are a pair of links 32 of the form clearly shown in Figure 1. One of these links extends toward and is pivoted to each of the members 25 by a pin 33. The respective assemblies are maintained by cotter pins 34 and 35. Each of the links 32 is of curved shape, as shown in Figure 6, to permit relative movement thereof in the same plane as indicated in such figure. The disc 28 is adapted to partake of rotary movement throughout approximately 180°. In the full line position of the parts of Figure 6 the members 25 are drawn to their extreme inward limits, the pivotal connection of each of the links with the disc 28 lying substantially in line with and between the pivotal connection of the other link with the disc and the pivotal connection of such other link with its cooperating member 25. In order to permit such movement the links are shaped in the peculiar manner above referred to. Inward movement of

the members 25 is automatically limited by engagement of the inner end of each link with the curved portion of the other link. Rotation of the disc 28 in the opposite direction moves the members 25 outwardly, such outward movement being automatically limited by engagement of projections 36 on the respective links, as shown in Figure 1.

The applying device is applied to the drum head by simply placing the same thereon and moving the applying device outwardly until the lugs 19 and 20 engage the inner surface of the flange 6. One of the members 25 is disposed adjacent each end of the retaining device, as shown in Figure 1, and so that upon operation of the handle 30 the respective portions 27 of the members 25 will bear against the projections 12 of the retaining device and move the retaining device to applied position. The head is maintained in place on the drum by wedging engagement between the retaining device and the rim bead 4 and the flange 6, as well known in the art. The applying device is effective for drawing the ends of the retaining device together, as shown in Figure 3, whereupon a bolt 37 is passed through the respective eyes 14 and a nut 38 applied thereto and tightened up to maintain the retaining device in applied position. After the nut 38 has been tightened up the handle 30 of the applying device is turned in the opposite direction to move the members 25 apart, whereupon the applying device may simply be lifted off of the drum head and used on another drum. If it is desired to seal the retaining device in place against unauthorized tampering a sealing wire may be passed through the openings 16 in the lugs 15. A padlock or equivalent device may also be used.

Certain subject matter disclosed but not claimed in this application is claimed in my co-pending application Serial No. 32,163, filed July 19, 1935, which is a division of this application.

While I have shown and described a present preferred embodiment of the invention, it is to be distinctly understood that the same is not limited thereto but may be otherwise variously embodied within the scope of the following claims.

I claim:

1. A device for changing the diameter of discontinuous annular retaining means to hold a closure member in place on a container, comprising a base member engaging the closure member so that the base member is positioned by the closure member, means connected with said base member and engaging the retaining means adjacent the ends thereof and operable to change the diameter of the retaining means, and means for operating said last mentioned means to change the diameter of the retaining means.

2. A device for changing the diameter of discontinuous annular retaining means to hold a closure member in place on a container, comprising a base member engaging the closure member so that the base member is positioned by the closure member, means connected with said base member having portions respectively abutting protruding portions of the retaining means adjacent the ends thereof in a direction generally along the retaining means and operable to change the diameter of the retaining means without moving the ends thereof substantially out of alignment, and means for operating said last mentioned means to change the diameter of the retaining means.

3. A device of the class described, comprising means adapted to lie in contact with a head being

applied to a container and means connected with said first mentioned means adapted to engage expandible and contractible discontinuous annular head retaining means adjacent the ends thereof 5 and operable to move said retaining means to predetermined position.

4. A device for changing the diameter of discontinuous annular expandible and contractible head retaining means on a container or the like 10 comprising means adapted to lie in contact with the head, means connected therewith adapted to engage the retaining means and operable to move the retaining means to predetermined position, and means for operating said last mentioned 15 means to move the retaining means to predetermined position.

5. A device for changing the diameter of discontinuous annular expandible and contractible head retaining means on a container or the like 20 comprising means adapted to lie in contact with the head, means connected therewith having portions shaped to operatively engage the retaining means adjacent the ends thereof and operable to move the retaining means to predetermined position, and means including link means for operating said last mentioned means to move the retaining means to predetermined position.

6. A device of the class described, comprising a pair of cooperating arms having portions respectively abutting protruding portions of discontinuous annular expandible and contractible retaining means adjacent the ends thereof in a direction generally along such means, and means separate from said arms for operating the same 35 to change the diameter of said retaining means without moving the ends thereof substantially out of alignment.

7. A device for changing the diameter of discontinuous annular expandible and contractible 40 head retaining means on a container or the like comprising means adapted to abut portions of the retaining means adjacent the ends thereof in a direction generally along the retaining means so as to be adapted to move such portions in said 45 direction without moving the ends of the retaining means substantially out of alignment and means including a rotatable operating shaft whose axis extends substantially perpendicular to the plane of movement of said first mentioned 50 means for operating said first mentioned means.

8. A device of the class described, comprising an operating handle and cooperating arms separate from said handle but connected therewith and relatively movable upon operation thereof for abutting portions of expandible and contractible discontinuous annular retaining means adjacent the ends thereof in a direction generally along the retaining means for moving said retaining means to predetermined position without moving the ends thereof substantially out of 10 alignment. 5

9. A device of the class described, comprising a base member, cooperating means pivotally connected directly to said base member for engaging expandible and contractible discontinuous annular retaining means adjacent the ends thereof and means for pivotally moving said first mentioned means to change the diameter of the retaining means. 15

10. A device of the class described, comprising 20 a base member, cooperating means pivotally connected with said base member for engaging expandible and contractible discontinuous annular retaining means adjacent the ends thereof and means including rotatable operating means and 25 link means connecting said first mentioned means thereto for pivotally moving said first mentioned means to change the diameter of the retaining means.

11. A device of the class described, comprising 30 means adapted to lie in contact with a head being applied to a container, means connected with said first mentioned means adapted to engage expandible and contractible discontinuous annular head retaining means adjacent the ends thereof, 35 and means movable generally parallel to the plane of the retaining means for operating said second mentioned means to move the retaining means to predetermined position.

12. A device of the class described, comprising 40 a base member, cooperating means pivotally connected with said base member for engaging expandible and contractible discontinuous annular retaining means adjacent the ends thereof, a rotatable member, link means pivoted to said first 45 mentioned means and to said rotatable member and a handle for rotating said rotatable member to pivotally move said first mentioned means to change the diameter of the retaining means.

GUY O. CONNER. 50
